UNITED STATES PATENT OFFICE.

HERMAN B. KIPPER, OF MUSKEGON, MICHIGAN.

APPARATUS FOR PRODUCING CYANIDS FROM NITROGEN OR AIR.

1,322,026.

Specification of Letters Patent. Patented Nov. 18, 1919.

Application filed February 19, 1918. Serial No. 218,063.

To all whom it may concern:

Be it known that I, HERMAN B. KIPPER, a citizen of the United States of America, residing at Muskegon, in the county of Muskegon and State of Michigan, have invented certain new and useful Improvements in Apparatus for Producing Cyanids from Nitrogen or Air, of which the following is a specification.

10 The present invention relates to improvements in apparatus for producing cyanids and analogous compounds from nitrogen or air, and is based on the principle that if nitrogen or air is passed over sodium carbonate, carbon and iron at a temperature of about 900 to 1000° centigrade, nitrogen will be absorbed and cyanids, or similar compounds produced.

To commercially utilize this well known 20 reaction many attempts have been made during the past thirty years to produce an apparatus for this purpose, which, however, have not been successful.

In the accompanying drawing which 25 forms part of this specification, and in which similar reference characters denote corresponding parts, Figure 1 is a more or less diagrammatic sectional view of the apparatus; Fig. 2 a cross section on line 2—2 of Fig. 1; Fig. 3 a cross section on line 3—3 of Fig. 1 and Fig. 4 an enlarged sectional view of the feeding end of the rotary reacting cylinder.

In the drawing A denotes a producer or 35 furnace which is fed with coke, preferably petroleum coke or other ashless fuel, through a hopper or charge opening B. From one side of this furnace leads a cylinder or pipe D into a suitably mounted revolving steel 40 cylinder E. This cylinder E is lined with an outer layer e' of insulating bricks and a second or inner layer e'' of refractory lining such as magnesia or soapstone, which will withstand the action of fused alkaline carbonates. The temperature in the cylinder E is adapted to be maintained above 900° centigrade. F is a feed pipe arranged at a slant and leading through the pipe D into the open end of the revolving cylinder E, adjacent said pipe. H and I are regenerator stoves of well known construction, each divided into a plurality of longitudinal flues h', h'', h''' which communicate with each other alternately at their opposite ends. The 50 regenerators H, I are provided with blowers or fans H', I' and discharge passages H'',

I'' leading to the chimney (not shown). These regenerators are connected at one end by pipes i, i' having valves i'' to a pipe j leading into the bottom of the furnace A 60 and at the opposite end by pipes k, k' to a cylinder or pipe L, which communicates with the open end of the revolving cylinder E opposite the feed F. The pipes k, k' also communicate with a pipe l leading into another 65 revolving cylinder K having also a slanting feed K' and which serves as a preheater. The opposite end of the preheater communicates through a pipe m with the feed F. The cylinder or pipe L is formed at its bottom 70 with a spiral feed M of usual construction. N denotes a pipe for the admission of nitrogen gas. Any suitable means for operating the cylinders E and K may be employed, such as wheels o or the like.

75 The mode of operation of this apparatus is as follows:

The finely divided reacting material, such as sodium carbonate, carbon and iron, is introduced first into cylinder K by pipe k' 80 and passing through the cylinder is preheated to a temperature of 400 to 600°. This preheated material is then fed through suitable means such as a spiral or other conveyer into the connecting slanting pipe F through 85 which it slides down by its own gravity. The furnace A receives a certain amount of ashless fuel such as petroleum coke or the like. Since preheated air is fed into the fuel bed contained in furnace A, the temperature developed may be made very readily to exceed 900° C., and by regulation of the temperature of the preheated air the reacting temperature derived may readily be established and maintained in cylinder E. It is necessary to use an ashless fuel in furnace A since any fuel containing ash will give so bad a clinker as to render furnace A inoperative.

95 After completion of the reaction in cylinder E, the cyanids and analogous compounds formed together with any material not acted upon will leave the cylinder through the opening leading from the latter into the pipe L, by itself, when the cylinder is entirely filled or through a suitable conveyer such as a spiral or the like which may be arranged within said opening or passage; and fall down onto the conveyer M. Nitrogen gas will be fed through pipe N into the cylinder L in order to surround the 100 cyanids and analogous compounds with an atmosphere of nitrogen during cooling.

Part of the producer gas leaving the cylinder E flows through cylinder L to pipe l and thence to the preheater cylinder K and another part of the producer gas leaving the cylinder E is fed through the pipes k, k' to the regenerators H and I. While the producer gas flowing from the reacting cylinder E mixed with air is being fed through regenerator H, the fan I' blows air through regenerator I and into furnace A. Subsequently when regenerator I has become sufficiently cool, producer gas and air are fed through it and passed through discharge I² to the waste heat stack, while regenerator H is used for preheating the air to be fed to furnace A. As mentioned, a portion of the producer gas leaving E is used for preheating the reacting materials in cylinder K and the gases burned in the latter are led to the waste heat stack through m.

The construction shown is of course only one embodiment of my invention. It is understood that the apparatus may be modified in various ways without departing from the principle of my invention, and I therefore do not wish to restrict myself to the details shown and described.

What I claim and desire to secure by Letters Patent is:

1. An apparatus for producing cyanids or the like, consisting of a revolving cylinder for the reacting material, a fuel furnace directly connected with said cylinder, a preheater having a feed leading into the same and a feed leading from the same into said cylinder and regenerators communicating each at one end with said furnace and at the opposite end with said cylinder and the preheater.

2. An apparatus for producing cyanids or the like, consisting of a revolving cylinder for the reacting material, an ashless fuel furnace directly connected with said cylinder, a revolving preheating cylinder having a feed leading into said cylinder and a feed leading from said cylinder into said first named cylinder, and regenerator stoves

each having longitudinal flues alternately communicating with one another, said stoves 50 communicating each at one end with said furnace and at the opposite end with said first named cylinder and the said preheating cylinder.

3. An apparatus for producing cyanids 55 or the like, consisting of a revolving cylinder for the reacting material, an ashless fuel furnace directly connected with said cylinder, a preheater having a feed leading into the same and a feed leading from the same 60 into said cylinder, and regenerator stoves each having flues alternately communicating with one another, said stoves communicating each at one end with said furnace and at the opposite end with said cylinder 65 and the said preheater.

4. An apparatus for producing cyanids or the like, consisting of a revolving cylinder for the reacting material, a fuel furnace directly connected with said cylinder, 70 a preheater having a feed leading into the same and a feed leading from the same into said cylinder, and regenerator stoves each having flues communicating with one another, said stoves communicating each at 75 one end with said furnace and at the opposite end with said cylinder and the said preheater.

5. An apparatus for producing cyanids or the like, consisting of a revolving cylinder 80 for the reacting material, a fuel furnace directly connected with said cylinder, a revolving preheater having a feed leading into the same and a feed leading from the same into said cylinder and regenerator 85 stoves each having flues communicating with one another, said stoves communicating each at one end with said furnace and at the opposite end with said cylinder and the said preheater. 90

In testimony whereof I affix my signature in presence of two witnesses.

HERMAN B. KIPPER.

Witnesses:

WALLACE FOOTE,
GRACE VANDERZYL.
